ADJUSTABLE SHIM

Leon F. Urbain, Chicago, Ill.

Application February 10, 1940, Serial No. 318,314

21 Claims. (Cl. 254—104)

This invention has to do with a shim and more particularly relates to one of novel shape and form especially adapting it for use cooperatively, interadjustably and interlockably with another similar shim.

My improved shim, while suited for use in any art that requires the leveling or blocking of parts, is especially useful in the building construction trade. In the construction of a building, for example, shimming is generally necessary beneath such parts as floor sills, floor sleepers, joists, stringers, window sill finishing pieces, window or door jamb finishing pieces and furring strips. Shingles are most frequently used for this purpose. When a shingle is so employed it is first pressed or driven, thin edge first, sufficiently far to dispose the required body thickness beneath the part being levelled, and then the remaining butt portion is broken off. These butt portions are simply discarded because they are awkward to carry until such a time, if ever, when the thinnest edge thereof would be insertable beneath or between parts to be spread. Consequently, when only the tip of a shingle is used, practically the whole shingle is thrown away. The waste is tremendous. It is estimated that 70 per cent of the bulk in every bundle of shingles carried onto a job to be used as shims is lost through waste of this nature. Further waste is often incurred, when the work is finished, by simply abandoning any partially depleted bundles of shingles, for once a bundle is broken, considerable time would be necessary in re-packaging the lot to ensure their reaching a subsequent job in perfect condition. As a general rule, therefore, the smallest building project requires a bundle of shingles earmarked for shims.

An object of the present invention is the provision of a new, compact, easily packaged and transported shim of inexpensive structure that will obviate the above mentioned waste.

A further object of this invention is the provision of an improved shim member of which a plurality are conveniently carried by a tradesman as a carpenter in his apron. Shingles, for instance, are long and interfere with essential body movements such as stooping.

A further object of this invention is the provision of a shim member made from a material as sheet metal which indefinitely retains its shape and thus remains where it is originally lodged despite temperature and humidity changes.

An additional object of the invention is the provision of a novel shim that is cooperably ad-

justable in interlocking relation with another identically constructed shim.

The above and other desirable objects of the invention will become apparent upon reading the following description with reference to the single sheet of drawings comprising a part of this specification and wherein:

Fig. 1 is a fragmentary horizontal sectional view taken through a vertical building wall on the line 1—1 of Fig. 2, and showing in side elevation a co-assembled pair of shims, each of which embodies one form of the invention;

Fig. 2 is a vertical fragmentary sectional view illustrating, in end elevation, two pairs of said shims in position for vertically aligning a furring strip;

Fig. 3 is a plan view of a pair of my improved shims of the character shown in Figs. 1 and 2, illustrating such shims in interlocked assembly;

Fig. 4 is a side elevational view showing one of the shims as those in Figs. 1 to 3 in the inverted position;

Fig. 5 is a view similar to Fig. 3, showing a pair of modified shims in co-assembled relation;

Fig. 6 is an end elevational view taken on the line 6—6 of Fig. 5;

Fig. 7 is a fragmentary plan view illustrating a pair of shims as those illustrated in Figs. 1 to 3, but having transverse ribs or corrugations; and

Fig. 8 is a side elevational view taken on the line 8—8 of Fig. 7.

While my improved shim has a definite immediate demand in the building trade and is herein illustrated and described with reference to particular uses in such trade, it should be understood that the device in its present or modified form is equally capable of utility in many other fields. For example, when stamped from heavy gauge sheet steel, the shim is useful for leveling light or medium weight machinery preparatory to grouting, and when cast of iron or other sufficiently strong material it is useful for leveling heavy machinery or for use in conjunction with, or in lieu of, tie plates beneath railroad rails. The uses are too numerous to attempt an exhaustive list.

Referring now to the drawing, and particularly to Figs. 1 to 4 which illustrate one embodiment of the invention, this embodiment will be seen to be in the form of a substantially U-shaped member 10. Said member 10 may be formed either by stamping or casting. When the member is of comparatively light weight, as that illustrated in the drawing, it will usually be stamped from sheet metal, although it may be shaped from

any other material which has sufficient strength, such as a phenol condensation composition or other plastic materials.

In Figs. 1 to 3 the shim member 10 is shown in association with a similarly shaped member 10a. Said shim member 10 comprises a pair of legs 11 and 12 which extend in parallelism and in the same direction from a base section 13. Each of the legs 11 and 12 has a rounded edge section 14, which sections serve as guide-ways at the entrance to a slit 15 between said legs. The leg 11 has stamped therein a longitudinal cam section 16 which is concavo-convex in shape. This cam section 16 protrudes the furthest from the obverse face of the shim at its end nearest the base section 13, and gradually diminishes in the amount of protrusion as the extended end of the leg 11 is approached, said section 16 having zero protrusion at some such point as 17.

The opposite leg, 12, of the shim 10, in Fig. 3, is for the most part concealed below a leg member 11a of the shim 10a, said leg 12 constituting a locking section of the shim 10 since it is disposed in frictional engagement with the under or reverse side of the leg 11a. Inasmuch as the shim 10a is identical with the shim 10, all designated parts thereof are indicated by respectively corresponding reference characters with an *a* added. The frictional engagement between the locking legs 12 and 12a and the cam-bearing legs 11 and 11a is increased in efficiency by knurling or otherwise roughening the faces of these members which are contiguously disposed, as indicated at 18 and 18a. Thus, in Fig. 3, the obverse faces 18 and 18a of the legs 12 and 12a are roughened as are the reverse faces of the legs 11a and 11 respectively engaged thereby. Such roughening of these faces may also be effected by applying a coating thereto which is rough in nature, as, for example, a galvanized coating, or a surface deposit obtained by means of an electrolytic process.

It will be observed in Fig. 3 that the interlocked shims 10 and 10a may be adjusted axially relatively to one another, and that they are movable relatively endwise incident to being assembled in the relation there shown. Such assembly is facilitated because of the legs 12 and 12a being relatively displaced flatwise of the shims whereby the legs 11 and 12 diverge as shown in Fig. 4.

One use of a pair of shims as 10 and 10a is illustrated in Figs. 1 and 2. In these figures a furring strip 19 is shown in association with the inner face of a brick building wall 20 comprising bricks as 21 separated and held together by mortar 22. In order that the inner face of the wall, consisting of laths 23 and plaster 24, will be truly vertical, pairs of the shims as 10 and 10a are disposed between the furring strip 19 and said wall 20. These furring strips 19, which are spaced horizontally along the wall 21 at intervals for coinciding with the adjacent ends of laths as illustrated in Fig. 1, are held in place to the wall by means of nails 25. Said nails 25 are driven through the furring strips 19 at those points where they will strike and embed themselves in the mortar between the bricks. Now it will be understood that when the comparatively rough brick work is not truly vertical or free of surface unevenness, the strips 19 may be selectively spaced therefrom by means of the shim members as 10 and 10a so as to cause the strips 19 to lay vertical. When the shims 10 and 10a are extended axially, Figs. 1 and 3, sections of less protrusion upon the cams 16 and 16a will be in registry with

the strip wherefore they will permit the strip to occupy a position quite close to the wall 20. If the shims 10 and 10a are moved axially together, higher points upon the cams 16 and 16a will be carried between the wall 20 and the strip 19 to displace the strip further from the wall. Thus the shims 10 and 10a are adjusted to cause the strip 19 to occupy the desired vertical position.

Said cams 16 and 16a also are adapted to receive the fastening means as the nails 25 within the opening 26 formed jointly by the slits 15 and 15a. Said fastening means 25 therefore serves as a stop to abut against the legs as 11 and 12 of the shims and prevent their vertical displacement. Axial displacement of the shims as 10 may be prevented by driving small nails through holes as 27 and 28 respectively at the ends of the shims.

When the shims are in their extended position in which the cams 16 and 16a displace the strip 19 but slightly, the holes 27 and 27a will be separated the most distantly and will thus be exposed upon opposite sides of a piece as 19, and when the shims are moved toward the opposite extreme of relative adjustment in which the cams 16 and 16a are arranged for displacing the member as 19 the greatest distance, the holes 28 and 28a will be accessible upon opposite sides of said member. Hence, this arrangement of the holes as 27 and 28 insures that at least one of them will be exposed, at a side of a member being positioned, in any adjusted position of the shims.

A slit as 15 may or may not be provided between the legs as 11 and 12 of the shims, but when such a slit is provided it enables the shims to have a holding member as the nail 25 centrally located with respect thereto. In this manner the force of a piece as the upright 19 is applied more evenly upon the cams 16 and 16a for snugly retaining the friction surfaces as 18 in engagement with the obverse face of the cam-bearing leg as 11a in interlocking relation therewith.

While a shim 10 is usable alone, it is especially adaptable for use complementally with a shim as 10a. When the shims are used in pairs their cams as 16 divide the load impressed thereon by the part being leveled, and in addition these cams, since they are inserted beneath opposite sides of said part, tend to hold said part level. In fact, if the part beneath which the cams are being inserted is warped or otherwise distorted so that it will not stand upright when supported upon a level footing, one of the shims may be inserted a greater distance than the other so as to cam one side of the part a greater distance than the other and thus tilt said part to correct for its deformity and cause it to set upright, perpendicular or at any selected degree of angularity.

A second embodiment of the invention is shown in Figs. 5 and 6. In each of these figures there is shown a shim 50 having a base section 51 from one side of which spaced legs 52 and 53 project in the same direction. Each of these legs has upon it a cam section 54, which in the present instance is formed by die-pressing the same so as to cause the cams to protrude outwardly from the shim's obverse face. These cam members 54 protrude the furthest at their ends nearest the base section 51 and diminish in the amount of such protuberance as the projecting ends of the legs are approached.

The base section 51 of the shim 50 is arched upwardly from its obverse face to form a bridge 55 having shoulders 57 at opposite sides of the bridge. The underside of these shoulders 57 are

sufficiently elevated to slidably receive the edge sections as 58 bordering opposite sides of a cam member as 54a upon a different and similarly constructed shim 50a. The bridge 56 is of sufficient height to telescopically receive a cam member as 54a of such a similarly constructed shim. Since the shims 50 and 50a are identical, the designated parts of the shim 50a are identified by corresponding reference characters with the letter *a* added.

Shims 50 are employable in the same manner as shims 10, above described, either singly or in combination with other shims as 50a. A pair of shims 50 and 50a are relatively adjustable axially for placing cam sections of different thickness beneath opposite edges of a piece being shimmed. Inasmuch as the shims shown in Figs. 5 and 6 have twice the number of cam sections as the shims in the lower numbered figures they are adapted to support twice the load. A pair of the shims as 50 and 50a provide four areas of support against a piece being shimmed, two areas of support being at one edge of the piece and likewise two areas at its opposite edge. Obviously, such distribution of the areas at which the cams 54 and 54a exert force upon the shimmed piece result in a firm support therefor. Furthermore, any irregularity in said piece may be compensated for by sliding one of the complementary paired shims further beneath the edge with which it is associated, and thus the piece may be tilted and held in any selected degree of angularity.

In Fig. 6 it will be seen that the shoulders 57 and 57a fit closely over the leg edge portions as 58a and 58 so as to be pressed into firm frictional engagement therewith when pressure is applied to the cams 54 and 54a. This frictional interlocking resists accidental displacement of the shims subsequent to their disposal in shimming relation with a piece. Such frictional engagement between the leg edge portions as 58 and the shoulders as 57a may be augmented by driving one or more nails through the holes as 59 into a wall, studding, or flooring or the like against which the reverse faces of the shims are placed. Here, as in the first described embodiment of the invention, the holes as 59 and 60 are arranged at opposite ends of the shims so at least one of these holes will be exposed adjacent to an edge of the shimmed part and thus accessible for receiving a nail.

Because of the greater number of camming sections provided by that form of shim shown in Figs. 5 and 6 it constitutes a light-weight comparatively heavy-duty device. This form of shim is therefore especially adapted for insertion beneath sections about the base of machinery or the like for leveling the same preparatory to grouting or otherwise permanently securing the machinery in place. When cams as 50 are made sufficiently heavy, by making them of heavy gauge sheet metal or by casting, they may very readily provide the permanent support for a machine or other body of great weight.

The modified form of shim, shown in Figs. 7 and 8, is in all respects like that in Figs. 1 to 3, excepting that there is additionally provided a series of transverse surface irregularities in the form of ribs or corrugations. These corrugations are indicated on the shim 11b by the reference numeral 75 and on the shim 11c by the reference numeral 76. Shim 11b corresponds to the shim 11 in Fig. 3, whereas the shim 11c corresponds to the shim 11a. Consequently the cam sections 16b and 16c respectively correspond to the cam sec-

tions 16 and 16a in Fig. 3. It becomes obvious upon examining Figs. 7 and 8 that the interfitting surface irregularities 75 and 76 offer considerable resistance to relative movement of the shims 11b and 11c axially of the cams 16b and 16c when said cams are pressed together beneath a load.

While I have shown and described only three forms of shim, it will be understood that other forms may be made without departing from the spirit of the invention and so it is intended that the invention shall not be limited to the present specific illustrative disclosure.

I claim:

1. A shim comprising a plate having a butt end and a bit end and including an elongated section extending between said ends and decreasing in thickness as the bit end is approached, and an adjacent frictional locking section of substantial uniform thickness projecting edgewise from said elongated section and connected therewith only at a butt end portion thereof.
2. A shim comprising a plate including juxtaposed sections of which one is a locking section, and an elongated tapered body upon the other of said sections, said shim being disposable in cooperative relation with a similarly constructed shim and each of said sections thereof being adapted to fit in overlapping relation with the non-corresponding section of such a similar shim during such cooperative relation.
3. A shim generally in the form of a plate-like body and including juxtaposed sections of which one is a locking section, and an elongated tapered formation upon the other of said sections, and said sections being relatively off-set normally of said body to facilitate sliding of the shim into assembly with another similar shim and with said locking section of each assembled shim in overlapping relation with the formation bearing section of the other.
4. A shim comprising a plate having butt and bit ends and including juxtaposed sections of which one extends between said ends and includes an elongated tapered cam body extending axially thereof, the other of said sections constituting a frictional locking section projecting laterally edgewise from said one section and being connected therewith only at a butt end portion thereof, at opposite ends of said plate to facilitate anchorage thereof to a supporting surface.
5. A shim comprising a pair of substantially flat spaced-apart legs, and an elongated concavo-convex tapered cam body upon at least one of said legs and decreasing in thickness as the free end of such leg is approached.
6. A shim comprising a longitudinal cam member and a locking member disposed laterally edge-wise thereof in a position to lay flatly in overlapping relation with the cam member of a different shim.
7. A shim comprising a pair of substantially flat spaced-apart legs, and an elongated tapered cam body upon at least one of said legs, said cam body being narrower than the face of the respective leg and projecting outwardly from such face and decreasing in the amount of such projection as the free end of such leg is approached.
8. A shim comprising a substantially flat U-shaped member including upon one of its legs an elongated tapered cam section decreasing in thickness as the free end of such leg is approached, a comparatively rough friction surface upon the cam-bearing leg at the side of said

member opposite to the cam, and a comparatively rough friction surface upon the other leg and at the opposite side of said member.

9. A shim comprising a substantially flat U-shaped member including upon one of its legs an elongated tapered cam section decreasing in thickness as the free end of such leg is approached, and said legs diverging flatwise of said member.

10. A shim comprising a U-shaped plate and wherein one of the legs has an elongated concavo-convex cam section tapering from the base toward the free end thereof.

11. A shim comprising a pair of substantially flat spaced-apart legs, an elongated concavo-convex tapered cam body upon at least one of said legs and decreasing in thickness as the free end of such leg is approached, and means substantially at opposite ends of said shim to facilitate anchorage thereof to a supporting surface, and said means at the end of said shim where said legs join being aligned with the space therebetween whereby it will be accessible through such space of a similar shim with which said shim is co-assembled with the legs of each shim in overlapping relation with the legs of the other.

12. A shim comprising a U-shaped member of which the legs are tapered to decrease in thickness from their base toward their free ends, and of which the base is arched transversely of said legs to adapt it to receive a leg of a different similar member.

13. A shim comprising a U-shaped plate, cam members extending longitudinally of the legs of said member and decreasing in thickness as the ends of said legs are approached, and the base of said member being constructed and arranged for frictionally and telescopically receiving a leg of a different similar member.

14. A shim comprising a plate including a base, parallel laterally spaced legs projecting in the same direction from said base, cam sections extending longitudinally of said legs and decreasing in thickness as the projecting ends thereof are approached, and said base embodying an arched bridge and shoulder portions at the ends of the bridge of such contour that said shim is disposable in cooperative relation with a similarly constructed shim with the bridge of each in telescopic relation with a leg of the other and with said shoulders of each in overlapping relation with marginal edge portions of the telescopically received legs.

15. A shim comprising a plate including a base, parallel laterally spaced legs projecting in the same direction from said base, concavo-convex cam sections integral with and extending longitudinally of said legs while decreasing in thickness as the projecting ends of the legs are ap-

proached, said base being arched to form a bridge between said legs, and the bridge being of such character that when two of said shims are co-assembled the bridge of each is adapted to receive a leg of the other and permit its axial movement therein.

16. A shim comprising a plate including a base, parallel laterally spaced legs projecting in the same direction from said base, concavo-convex cam sections integral with each of said legs and protruding outwardly from one face of the shim but protruding less distantly as the projecting ends of said legs are approached, said base being arched while also protruding outwardly from said shim face to effect a bridge and shoulder sections at the ends of such bridge, said bridge being sufficiently arched that when two of said shims are co-assembled the bridge of each is adapted to receive a leg of the other and to permit its axial movement therein, and said shoulder sections being of such elevation as to lie in close overlapping relation with the marginal edge portions of the leg received by their associated bridge.

17. A shim comprising a longitudinal cam member and a locking member disposed laterally thereof, and said locking member being of a character to receive a part of a different shim for telescopic adjustment therein.

18. The combination of a pair of shims, parallel longitudinal cams respectively upon said shims, and means common to said shims to prevent their relative displacement laterally of said cams while permitting their relative displacement axially of said cams.

19. A shim generally in the form of a plate-like body and including juxtaposed sections of which one is a locking section, and an elongated tapered formation upon the other of said sections, and said sections being relatively off-set normally of said body to facilitate sliding of the shim into overlapping relation with another similar shim and with the locking section of each shim upon the formation bearing section of the other.

20. A shim comprising a plate including an elongated cam section graduated in thickness from one end toward the other, and an adjacent locking section disposed laterally edgewise of said elongated section, and said locking section including elongated surface irregularities extending substantially transversely of said cam section.

21. A shim comprising a plate including juxtaposed sections of which one is a locking section, an elongated tapered cam body protruding from a face of the other of said sections, and locking means comprising elongated surface irregularities within each of said sections and extending substantially transversely of said cam body.

LEON F. URBAIN.
